UNITED STATES PATENT OFFICE.

CHARLIE EDWARD ENGBARTH, OF OCEAN SPRINGS, MISSISSIPPI.

CAR-MOVER.

No. 880,372.

Specification of Letters Patent.

Patented Feb. 25, 1908.

Application filed November 8, 1907. Serial No. 401,286.

To all whom it may concern:

Be it known that I, CHARLIE EDWARD ENGBARTH, a citizen of the United States, residing at Ocean Springs, in the county of 5 Jackson and State of Mississippi, have invented new and useful Improvements in Car-Movers, of which the following is a specification.

This invention relates to a device for moving cars, and has special reference to a device for insertion between the rails and the wheels of a car to "pinch" the car along the rails to the position or point desired.

The object of the invention is to provide a 10 simple, cheap and effective device for pinching and moving cars along tracks, one which can easily and conveniently be carried from place to place for use and operation, which can be quickly and securely applied to the 15 rail and engaged with the wheels of a car, and which presents novel features whereby the handle of the device may be readily lengthened or shortened to comply to the extent of leverage required in moving a car.

To these and other ends the invention resides in the novel construction of elements 20 and their arrangement in operative combination as will hereinafter be more fully described and claimed.

In the drawings,—Figure 1 is a side elevation of my device, illustrating in dotted lines its application upon a car wheel, Fig. 2 is a top plan view of the device, Fig. 3 is a side elevation of the lever employed with my device, Fig. 4 is a vertical sectional view upon the 25 line 4—4 of Fig. 1, Fig. 5 is a side elevation of a slight modification, Fig. 6 is a similar view of a further modified form of lever, Fig. 7 is a still further modified form of lever, and Fig. 8 is a section upon the line 8—8 of Fig. 5.

As illustrated in the drawings my improved car mover comprises primarily a pinch bar or lever 1 and a fulcrum block 2.

As illustrated more clearly in Fig. 4 of the 30 drawing the fulcrum block 2 comprises a central portion 3 and side plates 4 and 5, extending above the block and provided with the cylindrical openings 6 and 7. The side plates 4 and 5 are secured to the center block 3 by the screws or bolts 8, thus providing means whereby the plates may be readily and easily removed from the block.

The faces of the side plates 4 and 5 and center block 3 are provided near their lower 35 faces with the substantially diamond shaped

openings 9 and 10, undercut to provide a bearing surface below the fulcrum block 2 for the substantially diamond shaped gripping blocks 11 adapted to be received within the undercut openings provided by the block and 60 plates, and to form the V-shaped biting surfaces below the fulcrum block. By forming the openings and gripping blocks of the shape and form described it will be readily seen that should one of the biting faces of the blocks 65 become worn or broken, the block may be readily removed and reinserted within the opening of the fulcrum block to present a different biting face, and this process may be repeated until all four of the biting faces of 70 the block are worn or broken, when, of course, a new block must be substituted.

A pin 12, preferably cylindrical in cross section and provided upon each of its ends with reduced trunnions 13 is adapted for 75 engagement with the cylindrical opening 14 formed upon the lever 1, and the trunnions 13 are adapted for engagement with the openings 6 and 7 of the side plates 4 and 5.

The lever 1 comprises a face portion 15 having a toe 16 of lesser width than the face 15, and having its sides tapered or cut-away as at 17, to provide a bearing for the flange of a car wheel, and the lever portion 19 arranged at an angle from the face portion 15. The 80 lever portion 15 of the car mover is provided upon each of its side faces with a squared projection 20, the purpose of which will herein-after appear, and is tapered as shown in Fig. 3 of the drawings, and is provided near its 85 extremity with a squared portion 21 and a cylindrical threaded portion 22. A cylindrical washer 23 having a beveled outer face and a squared central orifice is adapted to engage the squared portion 21 of the lever 19 90 and to be retained thereon by a nut 24 engaging with the threaded portion 22 of the lever, and the purpose of this construction will herein-after be fully explained.

From the foregoing description it will be 100 observed that I have constructed an extremely simple device for pinching car wheels, one which may be readily placed upon a rail and securely held thereon by the biting teeth of the blocks provided within the fulcrum, 105 and the engaging face of the lever section being so constructed as to engage both the face and the flange of a car wheel.

The device just described is adapted for 110 use upon car wheels where not a great amount

of leverage is required to pinch the wheels, but for use upon heavy or loaded cars more power is required to successfully move the car, and to provide for this, I have produced 5 a handle extension 25 comprising a cylindrical tube having one of its ends provided with diametrically opposite cut-away portions 26 adapted to engage with the squared projection 20 provided upon each side of 10 the lever 19.

When the tube 25 is inserted upon the tapering lever 19, the washer 23 is adapted to bear upon the inner surface of the tube, and the cut away portions of the tube engage the 15 projections 20 upon the lever 15, thus presenting a substantial bearing for the tube.

Should still further leverage be desired an additional tube 27 may, as illustrated in Fig. 5 of the drawings, be inserted within the free 20 end of the tube 25 and be secured therein by the bolt 28 passing through suitable openings provided within the tubes 25 and 27, and an additional securing means 29, comprising a clamping strap provided with projecting ears 25 30 having openings for the reception of a bolt 31, the threaded portion of which being engaged by a nut or retaining element 32 which is adapted to press the ears of the strap together and rigidly securing the strap upon 30 the tube 25, at a point at or near the free end of the tube.

With the construction of devices for pinching cars just described it will be readily seen that I have provided simple and efficient 35 means comprising handles or levers readily attachable and removable from the main lever of the car mover whereby a greater or lesser amount of leverage may be attained as desired.

40 While I have described the preferred embodiment of my invention, it will of course be understood that minor details of construction may be resorted to without departing

from or sacrificing any of the advantages of the invention.

Having thus described the invention, what 45 I claim is:—

1. A device for moving cars, comprising a fulcrum block having removable sides and provided with biting teeth, an operating member pivoted between the removable sides, said member comprising a face portion and a toe portion of lesser width than the face and provided with outwardly inclined sides, and a lever arranged at an angle to the face portion. 50 55

2. A device for moving cars, comprising a fulcrum block having biting teeth and projecting sides, an operating member pivotally secured between the sides, said member having a face portion and a lever arranged at an angle to the face portion, squared projections upon two sides of the lever, and a tube having squared openings provided upon its face adapted to engage with the lever and the projections upon the sides of the lever. 60 65

3. A device for moving cars, comprising a fulcrum block having teeth on its under face and projecting sides, an operating member pivotally secured between the sides, said member comprising a face portion and a lever arranged at an angle to the face portion, a tube removably mounted upon the lever and provided with orifices near its free end, a second tube adapted to be inserted within 70 the first tube, a bolt connecting the tubes, and a retaining collar embracing the first tube and adapted to press it tightly against the second tube. 75

In testimony whereof I affix my signature 80 in presence of two witnesses.

CHARLIE EDWARD ENGBARTH.
